UNITED STATES PATENT OFFICE.

WILLIAM PRENTICE WILLETTS, OF ROSLYN, NEW YORK.

ICE CAN.

Application filed December 5, 1925. Serial No. 73,495.

This invention relates to ice cans of the high pressure type, one of the objects being to provide a simple and efficient structure having means combined therewith whereby air can 5 be forced to the bottom of the can so as to agitate the water while freezing. Various means for this purpose have been devised heretofore but generally they have been located inside of the can where they are likely 10 to become distorted by the removal of the ice and have caused undesirable depressions or the like in the cake of ice produced.

It is an object of the present invention to provide a means located within one of the 15 seams of the can whereby the air will be conducted to the bottom of the can, the resultant cake of ice being free of any grooves or recesses and there being no parts likely to be 20 come bent or otherwise injured by the removal of the ice from the can.

A further object is to provide a can formed of few parts and the parts of which can be assembled readily.

With the foregoing and other objects in 25 view which will appear as the description proceeds, the invention resides in the combination and arrangement of parts and in the details of construction hereinafter described and claimed, it being understood that changes 30 in the precise embodiment of the invention herein disclosed may be made within the scope of what is claimed without departing from the spirit of the invention.

In the accompanying drawings the preferred form of the invention has been shown.

In said drawings,

Figure 1 is a perspective view of a can constructed in accordance with the present invention.

Figure 2 is a side elevation thereof, one of the laps of a seam in the can being removed to show the air passage.

Figure 3 is a top plan view of the can.

Referring to the figures by characters of 45 reference 1 designates a can of the usual size and proportions, there being a seam along one corner portion of the can formed by a flange 2 which laps one side wall of the can. Ordinarily these lapping portions or flanges 50 have been attached directly to the walls of the cans by means of rivets. In the present instance the flange 2 of one of the seams of the can is spaced from the wall of the can 1 by spacing strips 3 and the rivets 4 used for 55 holding the lapping portions of the can together are extended through the spacing

strips so as to secure them in place. In the structure illustrated the rivets extending through one of the spacing strips are staggered with reference to the rivets extending 60 through the other spacing strip and those edges of the strips which are nearest each other are serrated so as to form between them a waved passage 5 which extends from the top of the can to a point adjacent the bottom 65 thereof. The strips 3 come together at the bottom of the can so as to close the lower end of the passage 5. An aperture 6 is formed in the wall of the can and communicates with the lower end portion of the passage 5. 70

It will be obvious from the foregoing that when air is directed under pressure into the upper end of the passage 5 it will flow downwardly therealong to the aperture 6 from which it will issue into the water being 75 frozen and thus keep it agitated.

Obviously, if desired, the strips 3 can be formed with straight edges instead of serrated edges. In that event the passage would be straight from top to bottom instead 80 of waved as shown. This modified arrangement is so obvious that it is not deemed necessary to show or describe the same in detail.

What is claimed is:

1. An ice can of the high pressure type 85 having flat lapping portions extending longitudinally thereof outside of the can, spacing elements separate from and located between the lapping portions forming an air passage therebetween within the outer portion 90 of one wall of the can, there being an air inlet at the upper end of the passage and an outlet connecting the lower end of the passage with the bottom portion of the can and securing means extending through the lapping portions and the spacing means for holding them clamped together.

2. An ice can of the high pressure type including flat lapping portions extending from the top to the bottom thereof outside 100 the can, said portions being integral with two of the walls of the can respectively, spacing elements separate from and interposed between said lapping portions and contacting at their lower ends, said spacing portions 105 being spaced apart for the greater portion of their length to provide an air passage within the outer portion of one wall of the can and open at one end, there being an aperture for maintaining communication between the 110 other end of the passage and the bottom portion of the can, and securing means extending

through the lapping portions and the spacing means for holding them clamped together and sealing the passage between its inlet and outlet.

- 5 3. An ice can of the high pressure type including a flat longitudinal flange upon one wall of the can lapping the outer face of another wall thereof, spacing strips separate from and interposed between said flange and the wall lapped thereby, said strips cooperating with the flange and wall to form an air passage within the outer portion of one wall
- 10

of the can and open at its upper end and closed at its lower end, there being an aperture for establishing communication between 15 said passage and the lower portion of the can, and securing means extending through the lapping portions and the spacing strips for holding them clamped together and for sealing the air passage except at its open end and 20 at the aperture.

In testimony that I claim the foregoing as my own, I have hereto affixed my signature.

WILLIAM PRENTICE WILLETS.
